CURTAIN ROD OR THE LIKE

Seymour Brenner, Miami Beach, Fla., assignor to Aluminum Screen Manufacturing Co., Miami, Fla., a corporation of Florida

Application May 29, 1957, Serial No. 46,396

Term of patent 14 years

(Cl. D21—1)

FIG. 1

FIG. 2

FIG. 3

I claim:

The ornamental design for a curtain rod or the like, as shown.
